UNITED STATES PATENT OFFICE.

AUGUSTUS FELLOWS, OF WASHINGTON, DISTRICT OF COLUMBIA.

BICYCLE-LAMP LOCK.

SPECIFICATION forming part of Letters Patent No. 703,907, dated July 1, 1902.

Application filed November 6, 1901. Serial No. 81,322. (No model.)

To all whom it may concern:

Be it known that I, AUGUSTUS FELLOWS, a citizen of the United States, residing at Washington, in the District of Columbia, have invented certain new and useful Improvements in Bicycle-Lamp Locks; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention is designed particularly to prevent the stealing of bicycle-lamps, and has for one of its objects to provide a means of exceedingly simple construction, durable, and cheap to manufacture.

Another object of the invention is to produce a bicycle-lamp lock of such a construction that it may serve not only as locking device, but also as a lamp-bracket.

Another object of the invention is to form the body portion of the lock and bracket of a single piece of bendable metal or other material.

Another object of the invention is to produce a lock or a lock and bracket for the lamp of an adjustable nature, that it may be used in connection with nearly, if not all, the bicycles at present upon the market.

A still further object of the invention is to produce a lamp lock and bracket for use in connection not only with a bicycle, but with any known vehicle.

My invention consists, essentially, of a single piece of metal or other material adapted to be formed into a band with the sides thereof normally parallel, means for connecting one end of the band to a lamp, means for attaching the other end thereof to a bicycle or other frame, means for locking the free ends of the band together, and, finally, means for drawing or contracting the normally-parallel sides of the band one-toward the other that a loop may be formed at each end thereof.

The invention will be described in detail hereinafter, pointed out more particularly in the appended claims, and illustrated in the accompanying drawings, in which—

Figure 1 is a side elevation of the invention connected at one end with a lamp and

at the other with a bicycle-frame, the view showing a portion only of the front frame of the bicycle. Fig. 2 is a top plan view of my invention. Fig. 3 is a view showing the body portion of the invention cut from a blank piece of material and showing also in dotted lines a reinforcing member, said body portion being broken away at one corner to show a portion of the said member in full lines. Fig. 4 is a view showing one of the free ends of the band struck up, forming a hook. Fig. 5 illustrates a modified form of my invention. Fig. 6 discloses another modification; and Fig. 7 is a top plan view of my invention, eliminating the lamp-attaching fingers and the means for locking the free ends of the band together.

Referring now to the drawings, the numeral 1 designates a bicycle-lamp, and 2 the upper front portion of a bicycle-frame, while the numerals 3 and 4 indicate arms pivoted by means of the rods or bolts 5 to the lamp, these parts all being of the usual construction.

Now taking up the construction of my improvement, the reference character 6 indicates a single piece of bendable metal or other material adapted to be formed into a band comprising spaced members 7 and 8, connected at one end with a web 9, and the free ends thereof bent one upon the other and forming substantially a second web. Formed of the same piece of material from which the band is constructed are projecting portions forming attaching or gripping fingers 10 and 11 and which are adapted to be bent that they may engage over the rods or bolts 12, to which the free ends of the arms 3 and 4 are pivoted and soldered or otherwise secured to the back of the web 9, while the other or free ends 13 and 14 of the spaced members 7 and 8, respectively, of the band are adapted to encircle the frame 2 of the bicycle. The free end of the spaced member 7 is provided with a staple or other form of hook 15, adapted to receive the opening or slot 16, formed in the free end of the other spaced member 8, said staple and slot registering one with the other in such a manner that one end of the spaced members 17 is engaged with the staple or other form of hook to lock the free ends of the spaced members

together upon the frame of the bicycle or other vehicle to which my invention may be applied.

Disposed intermediate the ends of the 5 spaced members 7 and 8 of the band are formed perforations 18 in direct alinement for the reception of the exteriorly - screw-threaded bolt or other equivalent element 19, which, coacting with a nut 20, is adapted to 10 contract the band at or near its center, thereby forming a loop of the spaced members at both ends of the band and clamping means of one of the loops for firmly holding the band upon the bicycle or other frame. Two sets 15 of perforations 18 are provided for the purpose of permitting an adjustment in the size of the loop encircling the bicycle-frame or other vehicle.

In the modification shown in Fig. 5 of the 20 drawings it is intended instead of forming the band in a single piece of material to construct same in different parts—*i. e.*, to pivot the ends of the spaced members of the band to the web 21—the other elements, including the attaching-fingers 10 and 11, of the invention being 25 the same as hereinbefore set forth.

I have illustrated in Fig. 6 of the drawings a band from which I have eliminated the attaching-fingers 10 and 11, thus producing an 30 attachment for locking a lamp supported in the well-known manner by a lamp-bracket 22, of ordinary construction and which is adapted to be first slipped through the skeleton inclosure formed by the arms 3 and 4, 35 and the open-ended box 23, receiving the bracket 22. Otherwise, with the exception of the attaching-fingers 10 and 11, this attachment for locking a lamp is the same as that illustrated in Fig. 1. I desire it understood 40 that while this construction shown in Fig. 6 of the drawings is intended particularly for a lamp-lock it will, even without the lamp-connecting means 10, serve also as a support for the lamp.

45 In order to prevent scratching or otherwise injuring the frame of the bicycle or other vehicle to which my improvement might be applied, I provide upon the inner faces of the free ends of the spaced members 7 and 8 a 50 lining of felt, rubber, or the like.

In some instances it may be found essential to reinforce the web of the band and which may be done by the addition of the plate 26, riveted or otherwise to the said web 55 9, as shown in Fig. 3. This plate 26 is secured to the lamp-connecting fingers 10 and 11 as well as to the web 9, and when the plate 26 is employed it is bent with the fingers for attachment with the lamp, as well understood.

I wish it understood that instead of the staple 15 shown in the drawings I may employ a hook 24, formed by "striking up" the metal or other material at the free end of the spaced member 7, as shown in Fig. 4 of the 65 drawings.

My invention can be applied to almost any form of lamp. Therefore it is to be understood that changes in form, proportion, and the minor details of construction may be resorted to without departing from the nature of the invention when adapting it to any particular kind, make, or variety of lamp. 70

Having thus described my invention, what I claim, and desire to secure by Letters Patent, is— 75

1. A device of the class described comprising a band whose sides are arranged normally parallel throughout their entire length, lamp-connecting fingers formed integral with 80 and at one end of the band, said fingers being arranged one at the top and the other at the bottom of the said end of the band, a reinforcing-plate carried by the said end and the said fingers, fastening means arranged at 85 the opposite end of the band, and means connected with the band for forming a loop at each end thereof.

2. A device of the class described comprising a band whose sides are arranged normally parallel throughout their entire length, lamp-connecting fingers formed integral with 90 and at one end of the band, said fingers being arranged one at the top and one at the bottom of the band, fastening means arranged 95 at the opposite end of the band, and means for contracting the normally-parallel sides of the band one toward the other whereby a loop is formed at each end of the band.

3. A device of the class described comprising spaced members, said spaced members being arranged an equal distance from each other throughout their entire length, a web for connecting respective ends of the spaced members, said web being formed integral with 100 the spaced members and having integral lamp-connecting fingers, one of said fingers extending above the spaced members, and one extending below the spaced members, means for fastening the opposite ends of the spaced 105 members one upon the other, and means connected with the spaced members for drawing each one toward the other, whereby a loop is formed at each end of the spaced members.

In testimony whereof I affix my signature 115 in presence of two witnesses.

AUGUSTUS FELLOWS.
